(57) CLAIM

The ornamental design for a barbecue grill, as shown and described.

DESCRIPTION

FIG. 1 is a front-right upper perspective view of a barbecue grill showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front-left upper perspective view thereof;

FIG. 9 is a front-right lower perspective view thereof;

FIG. 10 is a front-left lower perspective view thereof; and,

FIG. 11 is a bottom-left upper perspective view thereof.

The broken lines are included for the purpose of depicting portions of the barbecue grill that form no part of the claimed design.

1 Claim, 11 Drawing Sheets
